UNITED STATES PATENT OFFICE.

OLIVER W. JOHNSON, OF CLEVELAND, OHIO, ASSIGNOR TO THE CLEVELAND FOLDING MACHINE COMPANY, OF CLEVELAND, OHIO, A CORPORATION OF OHIO.

PAPER-FEEDING MECHANISM.

No. 895,465.

Specification of Letters Patent.

Patented Aug. 11, 1908.

Application filed November 2, 1906, Serial No. 341,671. Renewed January 6, 1908. Serial No. 409,562.

To all whom it may concern:

Be it known that I, OLIVER W. JOHNSON, a citizen of the United States, residing at Cleveland, in the county of Cuyahoga and State of Ohio, have invented a certain new and useful Improvement in Paper-Feeding Mechanism, of which the following is a full, clear, and exact description.

This invention is designed to feed sheets of paper to printing presses, folding machines, ruling machines and the like.

The object of the invention is to feed the sheets of paper to the receiving machine in proper position and relative to said machine, regardless of the manner in which said sheets are delivered to the feeding mechanism.

The invention includes a series of feed rollers, obliquely disposed with respect to the main feeding direction, and all having their top surfaces in the same plane, means for rotating said rollers simultaneously in the same direction, and an adjustable guide plate arranged adjacent to one end of said feed rollers, with its lower edge below their top surfaces and with its guiding face parallel with the direction in which it is desired that the paper sheets shall move into the receiving machine.

The invention consists of the combination of parts above mentioned, and in various more specific combinations, and sub-combinations of parts, and in certain details of construction which will be hereinafter described and definitely pointed out in the claims.

In the drawing, Figure 1 is a plan view of the improved paper feeding mechanism. Fig. 2 is a side elevation thereof with the driving sprocket removed. Fig. 3 is a vertical sectional view in the plane indicated by the bent line 3—3 of Fig. 1. Fig. 4 is an elevation of the delivery end of the mechanism; and Fig. 5 is a detail showing the manner of supporting the front ends of those rolls which do not extend to the side bars of the supporting frame.

Referring to the parts by letters, A represents a rectangle frame capable of being attached to the receiving machine in such manner that it may occupy a substantially horizontal position, but may be swung up out of the way when not in use. The means provided for securing this frame to the receiving machine are the following:

Two plates C are pivoted to the sides of this frame by means of aligned horizontal pivots c. These plates extend beyond the front end of the frame and are provided with vertically perforated hinge eyes c', by means of which they may be pivotally connected by pivot pins f with plates F, which latter plates are designed to be attached in any suitable way with the frame of the receiving machine. Locking pins c² are provided and they pass respectively through the plates C into holes in the side frame members when the frame is in a horizontal position, whereby said plate is held in that position. A guide plate B is adjustably secured to one of the side frame members, with its front face in a vertical plane, parallel with the direction in which it is desired that the paper sheets shall be moving when delivered into the receiving machine. This plate is laterally adjustable by means of two screws J, which screw through brackets a secured to the side frame member; and these screws are provided near their inner ends with annular grooves j which are loosely embraced by suitable plates b attached to the guide plate. By turning these screws in either direction, the guide plate may be moved to right or left as desired.

A plurality of feed rollers D are rotatably mounted in the frame A with their axes parallel to each other, but making an acute angle with the guiding face of plate B on that side of the rolls which face the delivery end of the device. The rolls at the forward end of the frame are mounted in bearings secured to one side member and to the front member of the frame; the rolls at the rear end of the frame are mounted in bearings secured to the other side and to the rear member of said frame; and the intermediate rolls being mounted in bearings on both side members of said frame. The top edges of these rolls are all in the same horizontal plane, which is slightly above the lower edge of said guide plate. One of the rolls D placed immediately of the others (thereby dividing said rolls into two series), is of larger diameter and serves as the driving roll. In each of the rolls D there is an annular groove d, there being two of such grooves d, d' in the driving roll. These grooves are so placed that those in the forward series of rolls, that is to say, the rolls in front of the driving roll,

are all in the same vertical plane with each other and with one of the grooves d in the driving roll, which plane is at right angles to the axes of said rolls. The grooves in the rear series of rolls are all of the same vertical plane with each other and with the other groove d' in the driving roll, which plane is likewise at right angles to the axes of the rolls. The driving roll may be driven by any suitable means. For example, it may be provided with a beveled gear d^2 on the projecting end of its supporting trunnion which engages with another beveled gear g rotatably mounted on a stub shaft secured to one of the side members of the frame A. This latter beveled gear is secured upon a sleeve g' to which is also secured a sprocket wheel g^2 by means of which it may be driven. The power to drive the sprocket wheel may come from the receiving machine through a sprocket chain g^3 indicated by dotted lines. It is preferable to employ a flexible driving member, like a sprocket chain, because it does not interfere with swinging the frame A upward out of the way.

The various rolls D are driven from the driving roll D' by two endless cord belts I, which are respectively wound about the several rolls in a peculiar manner, as shown in the drawing, which provides suitable traction for the rolls without applying thereto any unnecessary friction. For convenience in describing the manner in which the cord does so pass around these rolls, they may be grouped in pairs. It will be understood that the cord lies in the grooves d , d' referred to, and wholly below the top surfaces of the rolls. The cord passes over the feeding roll D' to the forward roll of the next pair, then down under said roll and up over the rear roll of the same pair; thence it passes forward and down around the forward roll of the next pair; and thence under and up over the rear roll of that pair; and thence to the forward roll of the next pair, and so on. After passing over the front roll of the series, it passes below all of the rolls in that series and up over the feed roll. The other cord passes in a similar manner from the driving roll around the rear series of rolls.

At the front end of the frame are two supplementary feed rolls E, E' whose axes are at right angles to the guide face of the plate B. These may be driven by a cord belt running over grooved pulleys e e' secured to said rolls respectively, and a grooved pulley g^4 secured to sleeve g' . When now a sheet of paper is dropped upon these feed rolls D, D', it will be carried forward toward the receiving machine, and will also be carried sidewise toward and against the guide face of the plate B. By contact with that face, it will be prevented from moving further in the lateral direction, and will be so turned that its entire edge will come squarely into contact with the

guide plate,—after which it will be moved forward with its edge so in contact, and will therefore be moved in a direction parallel with said guide face toward the receiving machine. The supplementary rollers, E E', by which it is finally carried into said receiving machine, have no tendency to move it laterally but only straight forward in the required direction.

As before stated, this feeding mechanism is adapted for printing presses, and ruling machines; and when so used, it is desirable, and sometimes necessary, that the delivery of said sheets shall be accurately timed with respect to the movements of the receiving machine. To produce this result, hold-back means are provided,—that is to say, means which will check the advance of the sheets, and will release them at the proper time with respect to movements of the receiving machine. This hold-back device consists of a rock shaft H mounted transversely in frame A below the feed rolls, and a series of arms h secured to said rock shaft having upwardly turned fingers h' which may project into the path of the advancing paper sheet just in front of the front supplementary feed roller E'. This rock shaft may have an arm h² to which is attached a forwardly extended link h³ whose front end may be supported in a position to be engaged by a cam K attached to some rotary part of the receiving machine.

It may be necessary to employ a tightener for one or both of the cord driving belts. Such a tightener may be a lever M pivoted to an arm N which is in turn secured to a transverse bar A' forming a part of the frame A. The lever may have a grooved sheave m mounted in its end, engaging with the top of the lower stretch of the cord loop; and this lever arm may be pulled down by means of the head p on a screw P which screws into said cross bar,—said head having an annular groove p' into which projects the forked end of the other arm of said tightener lever.

It is sometimes desirable that the feed frame be not swinging out of the way on a horizontal axis, but that it be swinging on a vertical axis while still in a horizontal position. It is for this reason that the frame is connected with the bracket plates F on vertical pivots f. Either one of these pivots may be withdrawn and the frame may be swung around upon the other into any desired position.

Having described my invention, I claim:

1. In a paper feeding device, the combination of a frame, with a series of rolls mounted therein on parallel axes which are oblique to the delivery end of the device and with their top surfaces all in the same plane, and mechanism for rotating said rolls, a supporting device to which said frame is connected on a horizontal pivot, and means for connecting said device by vertical pivots with a suitable support.

2. In a paper feeding device, the combination of a frame, with a series of rolls mounted therein on parallel axes, which are oblique to the delivery end of the device, and with their top surfaces all in the same plane, said rolls being provided with circumferential grooves which are all arranged in the same vertical plane at right angles to the axes of said rolls, and a belt engaging with all of said rolls in said grooves which belt is not so thick as the depth of said grooves, and which, therefore, lies wholly below the top surfaces of said rolls.

3. In a paper feeding device, the combination of a supporting frame, with a series of rolls mounted therein on parallel axes, which are oblique to the delivery end of the device, and with their top surfaces all in the same plane, a driving roll of larger diameter than the others mounted in said frame on a parallel axis, and with its top surface in the same plane with the other rolls, each of said rolls being provided with circumferential grooves, which grooves are all in the same vertical plane at right angles with the axes of the rolls, a driving belt going around the driving roll and engaging with all of the other rolls in the said grooves.

4. In a paper feeding device, the combination of a supporting frame, with a series of rolls mounted therein on parallel axes which are oblique to the delivery end of the device, and with their top surfaces all in the same plane, a driving roll of larger diameter mounted intermediate of the others on a parallel axis and with its top surface in the same plane with the other rolls, the said driving roll having two circumferential grooves, and the rolls in front of said driving roll having each a circumferential groove in the same vertical plane at right angles to their axes with one of the grooves in the driving roll, and the rolls behind the driving roll having also each a circumferential groove which is in the same plane at right angles to their axes with the other groove in the driving roll, and two driving belts lying respectively in said grooves, the one extending from the driving roll forward in engagement with all of the rolls in the forward series and the other extending from the driving roll rearward and engaging with all the rolls in the rear series.

5. In a paper feeding device which includes a supporting frame, and a plurality of rolls mounted therein on parallel axes, which are oblique to the delivery end of the device, and with their top surfaces all in the same plane, with the following means for transmitting motion from one pair of said rolls to an adjacent pair, to wit;—a cord passing over both rolls of a pair, then down and under the first roll of the rear pair, then rearward and up and around the rear roll of that pair, then forward, down and under the front roll of the next pair, then rearward, up and over the

rear roll of that pair, and forward therefrom, and means for advancing said cord.

6. In a paper feeding device, the combination of a supporting frame and a series of rolls mounted therein on parallel axes which are oblique to the delivery end of the device and with their top surfaces all in the same plane,—said rolls being provided with circumferential grooves which are all located in the same vertical plane at right angles to the axes of the rolls, with an endless cord which passes up around a roll and then forward over and below the forward roll of the pair of rolls next in front of the roll first mentioned, then up and over the rear roll of that pair and forward 70 and down and under the first roll of the next pair, and up and over the rear roll of said pair, then forward and down and under the forward roll of the next pair, and so on, which cord finally passes over, around and 75 under the forward roll of the series and then back to the rear roll, and means for rotating one of said rolls.

7. In a paper feeding device, the combination of a supporting frame and a series of 90 rolls mounted therein on parallel axes, which are oblique to the delivery end of the device, and with their top surfaces all in the same plane, said rolls being provided with circumferential grooves which are all located in the 95 same vertical plane at right angles to the axes of the rolls, and an endless cord which passes up around the rear roll and then forward over and below the forward roll of the first pair of rolls in front of the rear roll, then 100 up and over the rear roll of that pair and forward, down and under the first roll of the next pair and up and over the rear roll of said pair, then forward and down and under the forward roll of the next pair, and so on, 105 which cord finally passes over, around and under the forward roll of the series and then back to the rear roll, with a belt tightener device engaging with the lower stretch of said cord and adjustable for the purpose of taking 110 up the slack therein, and means for rotating one roll of the series.

8. In a paper feeding device, the combination of a frame, with a series of rolls mounted therein on parallel axes which are oblique to the delivery end of the device, and with their top surfaces all in the same plane, a guide plate at one side of said frame with its lower edge below the plane in which the top surface of said rolls lie, and one or more rolls mounted in the frame at the front end thereof upon axes at substantially right angles to the guiding face of said guide plate, and means for rotating all of said rolls in the same direction.

9. In a paper feeding device, the combination of a frame having side and end members, with a series of rolls mounted in bearings secured to the side members of said frame, and other rolls mounted in bearings secured to one side member and to the front member,

and other rolls mounted in bearings secured to the other side member and to the rear member, all of said rolls having parallel axes which are oblique to the delivery end of the 5 machine and having their top surfaces all in the same plane, and means for rotating said rolls.

In testimony whereof, I hereunto affix my signature in the presence of two witnesses.

OLIVER W. JOHNSON.
